US0D1000376S

(12) **United States Design Patent** (10) **Patent No.:** **US D1,000,376 S**
(45) **Date of Patent:** **** Oct. 3, 2023**

(54) **POWER SUPPLY UNIT UNIVERSAL**

(71) Applicant: **EcoFlow Inc.**, Shenzhen (CN)

(72) Inventors: **Xi Chen**, Guangdong (CN); **Haibin Zheng**, Guangdong (CN)

(**) Term: **15 Years**

(21) Appl. No.: **35/514,921**

(22) Filed: **May 11, 2022**

(80) **Hague Agreement Data**

Int. Filing Date: **May 11, 2022**

Int. Reg. No.: **DM/222616**

Int. Reg. Date: **May 11, 2022**

Int. Reg. Pub. Date: **Aug. 12, 2022**

(51) **LOC (14) Cl.** **13-02**

(52) **U.S. Cl.**

USPC **D13/103**

(58) **Field of Classification Search**

USPC D13/102, 103, 104, 105, 106, 107, 108, D13/109, 110, 118, 119, 184, 199; D14/356, 432

CPC Y02E 60/10; Y02E 60/50; H01M 10/44; H01M 10/46; H01M 10/465; H01M 10/482; H01M 2200/30; H02J 7/001

(57) **CLAIM**

The ornamental design for a power supply unit universal, as shown and described.

DESCRIPTION

1. Power supply unit, universal
2. Power supply unit, universal

1.1 : Front

1.2 : Back

1.3 : Left

1.4 : Right

1.5 : Top

1.6 : Bottom

1.7 : Perspective

1.8 : Perspective

2.1 : Front

2.2 : Back

2.3 : Left

2.4 : Right

2.5 : Top

2.6 : Bottom

2.7 : Perspective

2.8 : Perspective

Design 1: reproduction **1.1**: front view; reproduction **1.2**: back view; reproduction **1.3**: left view; reproduction **1.4**: right view; reproduction **1.5**: top view; reproduction **1.6**: bottom view; reproduction **1.7**: perspective view (front, top, right side); reproduction **1.8**: perspective view (back, bottom, left side). Design 2: reproduction **2.1**: front view; reproduction **2.2**: back view; reproduction **2.3**: left view; reproduction **2.4**: right view; reproduction **2.5**: top view; reproduction **2.6**: bottom view; reproduction **2.7**: perspective view (front, top, right side); reproduction **2.8**: perspective view (back, bottom, left side).

1 Claim, 16 Drawing Sheets
